(57) **CLAIM**

The ornamental design for a charging device for electronic vaporization device, as shown and described.

DESCRIPTION

This application is an application for reissue of U.S. Pat. No. D. 744,419, issued on Dec. 1, 2015, which corresponds to U.S. patent application Ser. No. 29/499,025, the entire contents of which are incorporated herein by reference.

FIG. 1 is a perspective view of a charging device for electronic vaporization device, showing our new design; FIG. 2 is a top plan view thereof;

FIG. 3 is a left side elevation view thereof;

FIG. 4 is a rear elevation view thereof;

FIG. 5 is a right side elevation view thereof;

FIG. 6 is a front elevation view thereof; and,

FIG. 7 is a bottom plan view thereof.

[The broken lines shown in the drawings are included for the purpose of illustrating environmental structure and form no part of the claimed design.]

The broken lines illustrate portions of the charging device for electronic vaporization device that form no part of the claimed design.

1 Claim, 7 Drawing Sheets

Matter enclosed in heavy brackets [ ] appears in the original patent but forms no part of this reissue; matter printed in italics indicates the additions made by reissue.
